GASEOUS ELECTRIC DISCHARGE DEVICE

Warren R. Walker, Short Hills, N. J., assignor
to General Electric Vapor Lamp Company,
Hoboken, N. J., a corporation of New Jersey

Application July 16, 1934, Serial No. 735,490

1 Claim. (Cl. 176—45)

The present invention relates to electric gaseous discharge devices generally and more particularly to apparatus for starting and operating the same.

5 A particular object of the invention is to improve the starting of mercury vapor arc lamps and the like. A further object of the invention is to improve the operation of the vacuum switch which is employed in my novel circuit. Other 10 objects and advantages of my invention will appear from the following detailed description or from the accompanying drawing.

The invention consists in a new and novel combination of elements as hereinafter set forth and 15 claimed.

In starting mercury vapor arcs of the Cooper Hewitt type it is customary to create a voltage surge of sufficient value to produce the necessary initial ionization by interrupting the flow of a 20 current through the arc stabilizing inductance. Until recently this has been accomplished by the use of a highly evacuated mercury switch, called a shifter, but I have now found that greatly improved starting can be attained with a highly 25 evacuated switch containing only solid contacts, as is disclosed in my co-pending application, Serial No. 647,016, filed December 13, 1932. In the use of the novel circuit there disclosed, however, it has been found that under some circumstances 30 the switch again closes the circuit before the energy which is stored in the condenser of which the usual starting band is a part has been dissipated. Under these conditions the switch short circuits this condenser, and thus permits the flow 35 of an extremely high current, far in excess of that for which the switch is designed. This excessive current flow tends to fuse the contacts of the switch, and thus is a source of considerable difficulty. I have now discovered, however, that 40 this difficulty can be entirely eliminated by a novel rearrangement of the elements employed in this circuit without in any way impairing the efficiency thereof in initiating an arc.

According to my invention this new result is 45 obtained by including a resistance of the order of at least a few ohms in the circuit which includes both the shifter and the condenser of which the starting band is a part. In the preferred circuit this result is obtained by the novel expedient of 50 shifting the connection of the starting band from the usual point between the shifter and the current limiting resistance to a point beyond said resistance. As a result said resistance is given the new function of limiting the condenser dis- 55 charge current flow through the shifter, as well

as its former function of limiting the current flow therethrough from the line. With the current which can flow through the switch or shifter as it closes thus limited the problem of insuring the opening of this switch is greatly simplified, 5 and at the same time the circuit is made exceedingly reliable and effective as a starting means for the mercury vapor arc, due to the fact that welding of the switch contacts is positively precluded.

10 For the purpose of illustrating my invention I have shown a schematic diagram of a preferred embodiment thereof in the accompanying drawing.

As shown in this drawing the mercury vapor 15 arc lamp 1 of the well known Cooper Hewitt type has a mercury cathode 2, a conventional starting band 3 of tinfoil or the like in electrostatic relation thereto, and a pair of anodes 4. The anodes 4 are each connected in the usual manner through 20 a ballast resistance 5 to an end of the autotransformer 6, said autotransformer being connected in turn to any suitable source of alternating current. The cathode 2 is likewise connected in the usual manner through an arc stabilizing inductance 7 to the midpoint of said autotransformer 6. A highly evacuated, solid contact switch 8, which is preferably of the type disclosed in my Patent 1,984,505, granted December 18, 1934, is arranged to be magnetically opened 25 by said inductance. One terminal of said switch, or shifter, as it is commonly called, is connected to the same side of the inductance as is the cathode 2, while the other terminal of said switch is connected through a resistance 9 of the order of 30 at least a few ohms, and preferably of from 60 to 100 ohms, to one end of said autotransformer 6 through one of said ballast resistances 5. The starting band 3 is connected to a point between 35 said resistance 9 and the resistance 5.

40 In the use and operation of this device, upon application of a suitable alternating current potential to the autotransformer 6 potential is applied between the anodes 4 and the cathode 2, but this potential is insufficient to initiate a discharge therebetween, as is well known. A current of the order of an ampere flows, however, from the midpoint of the autotransformer 6 through the inductance 7, shifter 8, the current limiting resistance 9 and ballast resistance 5 45 back to one end of said autotransformer. This current energizes said inductance and thus opens the shifter 8. A voltage surge is thereupon created within said inductance 7 which depresses the potential of the cathode 2 a thousand volts 50 55

or more below that of the starting band 3, which is maintained at a substantially constant potential during the surge by its connection, and the condenser formed by said cathode 2, starting 5 band 3 and the intervening glass dielectric is thereby simultaneously charged up to this potential difference. A disruptive discharge at the mercury cathode usually ensues, sufficient ionization being thus produced to permit the initiation 10 of an arc discharge from the anodes 4 to the cathode 2 at the existing potential difference therebetween. The aforesaid condenser is, of course, discharged when this disruptive discharge occurs. In some cases, however, the surge may 15 fail of its purpose, so that this condenser is still charged when the shifter 8 again closes, forming a closed circuit from the mercury cathode 2 through the shifter 8, and resistance 9 back to the starting band 3. The condenser is thereby 20 discharged, but the current is limited by the resistance 9 to a value which the shifter 8 can control without difficulty, whereas in the absence of the resistance 9 in this circuit this current reaches such proportions that the contacts 25 of the shifter frequently weld together, rendering the entire lamp inoperative. Hence as a result of this novel location of the resistance 9 with respect to the vacuum shifter 8 and the starting band 3 I have been able to eliminate a 30 serious difficulty which threatened to limit the use of a shifter of this type in a lamp starting circuit. I have furthermore found that the presence of this low resistance in this location in the starting circuit does not result in any ap- 35 preciable impairment of the starting of the lamp 1, but that on the contrary it tends to improve it due to the better operation of the shifter 8.

While I have described my invention by reference to a specific embodiment thereof it is to 40 be understood that it is not limited thereto, but

that it is likewise applicable to use in starting any type of discharge device wherein a similar problem is encountered, and that various omissions, substitutions and changes, within the scope of the appended claims, may be made therein 5 without departing from the spirit thereof.

I claim as my invention:

In combination, a mercury vapor arc device having a mercury pool cathode, at least one anode, and a conducting sheath for starting said 10 arc in electrostatic relation to said pool, whereby said pool and said sheath form the plates of a condenser, a connection from said sheath to a point of substantially constant potential during the starting operation of the lamp, an inductance in the lead to said cathode, means to complete a circuit through said inductance independently of said device, said means including an evacuated metal to metal contact switch which also completes a circuit through said condenser 20 and which is magnetically responsive to current flow through said inductance to open said circuit therethrough whereby a voltage surge is created which increases the potential difference between said cathode and said sheath and thus 25 charges said condenser, an impedance path around said switch through which the charge on said condenser can escape, said switch having an inertia such that it opens and again closes the circuits therethrough before the condenser is 30 completely discharged through said impedance path, and a resistance included within the aforesaid circuit containing said switch and condenser which limits the condenser discharge current through said switch to a value which will not 35 fuse said contacts when said contacts reclose before the condenser charge has been dissipated.

WARREN R. WALKER.
